UNITED STATES PATENT OFFICE.

GEORGE FEENEY AND THOMAS O'CONNOR, OF COLUMBUS, OHIO, ASSIGNEES OF ONE-TENTH TO TIMOTHY O'BRIEN, OF COLUMBUS, OHIO.

AUTOMATIC LOCK.

Application filed August 26, 1927. Serial No. 215,732.

This invention relates to a locking device for the doors of railway cars such as mail cars, baggage cars and express and box cars, the general object of the invention being to provide means for holding the latch of the door in locking position by a pair of members, one of which is held in operative position by air from the air line of the train and the other of which is moved into operative or inoperative position by a key, the parts being so arranged that the air operated device will move to operative position when the key is turned to move the other member into inoperative position so that it is necessary to shut off the air to the device and then turn the key before the device can be set to unlocking position.

Another object of the invention is to so arrange the parts that the hand operated device can be used to lock and unlock the door when the air has been shut off from the device.

A further object of the invention is to provide spring means for holding the air operated member in inoperative position at all times when the air has been shut off and the device is being used as a hand operated device only.

Another object of the invention is to so arrange the parts that the door latch can be moved to operative and inoperative position in the ordinary manner when the locking device is in inoperative position.

This invention also consists in certain other features of construction and in the combination and arrangement of the several parts, to be hereinafter fully described, illustrated in the accompanying drawings and specifically pointed out in the appended claims.

In describing our invention in detail, reference will be had to the accompanying drawings wherein like characters denote like or corresponding parts throughout the several views, and in which:—

Figure 1 is a fragmentary view of the exterior of the car, with parts broken away to show the interior, and showing the invention in use.

Figure 2 is a vertical sectional view through Figure 1.

Figure 3 is a vertical sectional view through the locking device.

Figure 4 is a front view of the device with parts broken away.

Figure 5 is a side view showing a modification.

Figure 6 is a section on line 6—6 of Figure 7.

Figure 7 is a vertical sectional view through the modified form of the device.

Figure 8 is a fragmentary view of the inside of the car, showing the modified form of the device in use.

Figure 9 is a view of the key engaging end of the shaft.

Figure 10 is an end view of the key.

Figure 11 is a side view of the key.

As shown in these views, A indicates a part of the car and B a part of the door thereof, this door being arranged to slide along one side of the inner wall of the car, as in the ordinary manner and said door is provided with a keeper member 1 which is adapted to receive the end of the latch 2

which is connected by a coupling 3 with a depending rod 4, the headed end of which extends into the casing 5 of the locking device which is fastened to the inner wall of the car and all of these parts are enclosed in a housing 6 fastened to the wall of the car. A spring 7 is placed on the rod 4 and has its upper end bearing against the coupling 3 and its lower end engages a cup-shaped part of a bushing 8 inserted in the top of the casing 5 and through which the rod 4 passes. Thus the spring tends to hold the latch 2 in engagement with the keeper member 1. A shaft 9 is journaled in the side wall of the car and has a handle 10 on its outer end and an arm 11 on its inner end which has a part engaging the latch 2 so that by manipulating the handle 10, the latch 2 can be depressed against the action of its spring to move it to releasing position.

The casing 5 is attached to the inner wall of the car and has a keyhole forming part 12 extending through said outer wall so that a key, such as shown at 13 in Figure 11, can be inserted in this hole from the outside of the car. The opposite part of the casing is formed with a socket forming ex-

2 tension 14 in which is placed a bushing 16 and a locking member 17 of rectangular shape has a cylindrical central portion 18 at one side thereof which slidably fits in the bushing. A second locking member 19 is arranged in parallel relation to the member 17 in the casing 5, and a flanged nut member 20 passes through an opening in the member 19.

10 A shaft 21 has its inner end rotatably and slidably arranged in an opening 22 which is formed in the member 17 and its extension 18 and this shaft is provided with the threads 23 which engage the nut member 20 15 in such a manner that when the shaft is turned, the nut member is moved forwardly or rearwardly according to the direction the shaft is rotated. The shaft is provided with a ratchet wheel 24 which is engaged by 20 a spring pressed dog 25 arranged in the wall of the casing 5 and the end of the shaft which fits in the keyhole is formed with a triangular shaped projection 25 and the three pins 26 and the key is formed with a 25 triangular shaped opening 27 to receive the projection 25 and the holes 28 for receiving the pins 26, so that when the key is placed in engagement with the projections on the shaft, the shaft can be turned by rotating 30 the key.

35 A coil spring 29 surrounds the shaft and the body of the nut member and has one end engaging a flange of the nut member and its other end engages the member 17, and this spring tends to force the member 17 against the wall of the casing 5, with its extension 18 in the socket forming part 14. A roller 30 is carried by the bottom of each of the members 17 and 19 and these rollers engage 40 the bottom of the casing. A pipe 31 has its upper end screwed in the extension 14 and this pipe is connected with the air system of the train, a passage 32 in the extension 14 connecting the upper end of the pipe with 45 the cylinder formed by member 14, and said pipe contains a valve 33 which is accessible from the inside of the car through an opening 34 formed in the housing 6. Thus the air entering the cylinder from the air system 50 will force the member 17 under the head of the rod 4 and against the action of the spring 29, when the valve 33 is open.

55 From the foregoing it will be seen that when the valve 33 is open, the air will force the member 17 against the pins 35 carried by the member 19 and if member 19 is in inoperative position, the member 17 will be moved under the headed end of the rod 4 and thus prevent lowering of the rod 4 and 60 the releasing of the latch 2. Thus it will be impossible to unlock the door of the car until the air in the air system of the train is released. As soon as this is done, the spring 29 will force the member 17 from under the 65 rod 4, the air in the cylinder exhausting back

through the pipe 31 to the train pipe. If the key is used while the air is on, the member 19 would push back the member 17, but before the rod 4 could be moved downwardly, said member 19 would move under the same 70 so that the parts would still remain in locking position and then when the member 19 was moved back to its original position, the air would cause the member 17 to follow it.

75 When the device is not to be operated by air, the valve 33 can be closed and then the member 17 will be held against the casing 5 by the spring 29 and it will remain in this position until the air is again turned on to the device. With the member 17 in inoperative position, the key is used to turn the shaft 21 to move the member 19 under the rod 4 to hold the latch in locking position or to move the member 19 from under the rod 4 to permit the latch to be moved to releasing position. Thus we have provided simple means for preventing the opening of the car door while the train is in transit, the locking means being actuated either by air or by a key, as desired.

80 In actual practice, the key is used to lock the parts and then if an attempt is made by a thief to unlock the door while the train is in motion and should he succeed in moving the key operated means to inoperative position, the air pressure in the cylinder would cause the member 17 to follow the member 19 and thus hold the door locked and prevent the thief from entering the car. It will be understood that the door cannot be unlocked 85 even by a key until the air pressure in the brake line is reduced to permit the air in the cylinder to escape.

90 The casing is made airtight by means of the gaskets 36 and a washer 37 is placed on the end of the piston forming part 18 to prevent escape of air from the cylinder formed by the part 14.

95 In the modification, the casing 5' is fastened to the under part of the car by the bolts 38 and the cover 39 of the casing is held to the casing by the bolts 40. The locking members 17' and 19' are of slightly different form from those shown in the other figures as the member 17' is provided with a beveled part 42 which is engaged by a projecting part 43 on member 19' when the two parts are engaging each other. The shaft 21' is provided with a collar 44 which engages a recess 45 in the member 17' and when the shaft is rotated, it is moved longitudinally and thus the collar 44 causes the member 17' to move with the shaft. The rod 4' is of considerable length, as shown in Figure 8, and the handle parts 10' for moving this rod are also of a slightly different form from that shown in the other figures. However, this form of the invention works the same as that first described.

100 In the modification, a roller 45 is placed on

the lower end of the part 4" of the rod 4' for engaging the locking member 17' and 19'.

The key shown is a difficult one to duplicate and the pins protect the triangle on the controlling shaft and the outer end of the shaft is housed deep so that it is impossible to turn the shaft with a tool other than the key designed for it.

10 It is thought from the foregoing description that the advantages and novel features of our invention will be readily apparent.

We desire it to be understood that we may make changes in the construction and in the 15 combination and arrangement of the several parts, provided that such changes fall within the scope of the appended claims.

What we claim is:—

1. A locking device of the class described 20 comprising a casing, a latching rod extending into the same, a pair of members movably arranged in the casing and when either one of which is arranged under the rod, will prevent movement of the same, means for 25 normally holding the members apart so that the rod may be lowered between them, key operated means for moving one of the members and compressed air operated means for moving the second member against the first 30 member.

2. A locking device of the class described comprising a casing, a latching rod extending into the same, a pair of members movably arranged in the casing and when either 35 one of which is arranged under the rod, will prevent movement of the same, means for normally holding the members apart so that the rod may be lowered between them, key operated means for moving one of the members, compressed air operated means for 40 moving the second member against the first member and means for shutting off the air supply when desired.

3. A lock of the class described comprising 45 a casing, a latching rod depending into the same, a pair of members slidably arranged in the casing and when either one of which is under the rod will hold the same in latching position, a spring arranged between 50 the two members for urging them apart, a piston formed on one member, a cylinder formed by a part of the casing, means for connecting the cylinder with a supply of compressed air to move the piston carrying member against the other member, means 55 for shutting off the air when desired and key operated means for actuating the other member.

4. A lock of the class described comprising 60 a casing, a latching rod depending into the same, a pair of members slidably arranged in the casing and when either one of which is under the rod will hold the same in latching position, a spring arranged between 65 the two members for urging them apart, a

piston formed on one member, a cylinder formed by a part of the casing, means for connecting the cylinder with a supply of compressed air to move the piston carrying member against the other member, means for 70 shutting off the air when desired, key operated means for actuating the other member, such means including a shaft having threads thereon, means for causing the rotation of the shaft to move the member and 75 key engaging means on the outer end of the shaft.

5. A lock of the class described comprising a casing, a latching rod depending into the same, a pair of members slidably arranged in the casing and when either one of which is under the rod will hold the same in latching position, a spring arranged between the two members for urging them apart, a piston formed on one member, a cylinder formed by a part of the casing, means for connecting the cylinder with a supply of compressed air to move the piston carrying member against the other member, means for 80 shutting off the air when desired, key operated means for actuating the other member, such means including a shaft having threads thereon, means for causing the rotation of the shaft to move the member, 85 a triangular shaped projection and pins on the outer end of the shaft and a key formed with a triangular shaped socket and round sockets for receiving the projection and pins on the shaft.

6. A lock for the doors of railroad cars comprising a casing, a rod connected with the latch of the car door and extending into the casing, a spring associated with the rod for normally holding the latch in latching position, a handle connected with the latch 100 for releasing the same and lowering the rod, a pair of locking members in the casing adapted to be moved alternately under the rod to prevent lowering of the same, a piston on one member, a cylinder formed by a part 105 of the casing and receiving the piston, means for connecting the cylinder with the air line of the car to move the piston carrying member against the other member, a valve within the car for closing the air line, a spring for 110 normally urging the piston in the cylinder when the air line is closed, a screw shaft for moving the other member and a key for operating said shaft.

7. A lock for the doors of railroad cars comprising a casing, a rod connected with the latch of the car door and extending into the casing, a spring associated with the rod for normally holding the latch in latching position, a handle connected with the latch 120 for releasing the same and lowering the rod, a pair of locking members in the casing adapted to be moved alternately under the rod to prevent lowering of the same, a piston on one member, a cylinder formed by a part 125 of the casing and receiving the piston, means for connecting the cylinder with the air line of the car to move the piston carrying member against the other member, a valve within the car for closing the air line, a spring for normally urging the piston in the cylinder when the air line is closed, a screw shaft for moving the other member and a key for operating said shaft.

of the casing, means for connecting the cylinder with the air line of the car to move the piston carrying member against the other member, a valve within the car for closing the air line, a spring for normally holding the piston in the cylinder when the air line is closed, a screw shaft for moving the other

member, a key for operating said shaft and rollers on the members and engaging the bottom of the casing.

In testimony whereof we affix our signatures.

GEORGE FEENEY.
THOMAS O'CONNOR.
